ATTORNEY

UNITED STATES PATENT OFFICE.

JOSEPH A. CONNER, OF SANTA CLARA, CALIFORNIA.

NUT-HULLER.

1,388,026.

Specification of Letters Patent. Patented Aug. 16, 1921.

Application filed February 1, 1921. Serial No. 441,637.

To all whom it may concern:

Be it known that I, JOSEPH A. CONNER, a citizen of the United States, and residing near Santa Clara, in the county of Santa 5 Clara and State of California, have invented certain new and useful Improvements in Nut-Hullers, of which the following is a specification.

My invention relates to a machine for removing the hulls from nuts, such as walnuts, 10 separating the one from the other and preparing the nuts for drying.

It is the object of my invention to provide a machine of the character indicated 15 equipped with means for preventing injury to the nuts in their passage therethrough; with means for effecting a positive discharge of the nuts and hulls therefrom; and with means for separating the nuts from the hulls. 20 It is a further object to provide a machine embodying the above indicated mechanisms which will be compact in form, simple in construction and highly efficient in its practical application.

25 In the drawing:—

Figure 1 is a side elevation of my invention.

Fig. 2 is a plan view of the same.

Fig. 3 is a sectional view on line 3—3 of 30 Fig. 2.

Fig. 4 is a sectional view on line 4—4 of Fig. 3.

Referring more particularly to the drawing, at 1—1—1—1 are shown four posts 35 mounted on base members 2 and having a cylindrical shell 3 rigidly mounted thereon by rivets 4. At 5 is a hopper concentrically arranged with relation to shell 3 and adjustably suspended thereover on posts 1 by 40 nut levers 6, the same being mounted on bolts 7 in bearings 8, said bolts passing through angular slots 9 in hopper 5. A reverse movement of levers 6 loosens the hopper so that it may be turned to the right or 45 left thereby raising or lowering the same by means of angular slots 9, a forward movement of levers 6 again locking the hopper in position.

Hopper 5 is provided with a central opening 11 provided with a flange 12 supporting a horizontally arranged circular brush 13 having a central opening 14 and supported at its outer edge by braces 15 attached thereto and to hopper 5.

55 At 16 is shown an annular member held in spaced relation to shell 3 and brush 13 by

bolts as 17 set in shell 3 and supporting a depending flexible curtain 18.

In axial alinement with openings 11 and 60 14 and mounted on base members 2, is a bearing member 19 having a stub shaft 20 mounted therein and provided with a set collar 21 at its lower end and having a bevel gear 22 keyed to its upper end as shown, the latter carrying a huller plate 23 of substantially 65 the same diameter as brush 13 and provided with baffle bars 24. This plate 23 is rotated at high speed by means of a gear 25 meshing with gear 22 and mounted on shaft 26 in bearings 27 and driven by pulley 28 from 70 a source of power not shown.

At 29 is a discharge plate mounted in rollers 30 on shell 3 and provided with a vertically arranged annular flange 31 just below and within the circle described by 75 huller plate 23. Within flange 31 the plate 29 is perforated as at 32 to engage a sprocket 33 mounted on shaft 26, so that when huller plate 23 is rotated at high speed the plate 29 is rotated in the same direction at a slower 80 rate of speed owing to the smaller size of sprocket 33 and its distance from the vertical axis of the revolving members. Shell 3 is provided with a perforated discharge 85 chute 34, and a baffle plate 35 is arranged as shown with one end terminating in chute 34 and the other end advanced a distance into close proximity to flange 31 so that material carried by plate 29 will be scraped off by member 35 and caused to fall into 90 chute 34.

At 36 is a cylindrical screen provided with a spiral element 37 extending from one end thereof to the other and attached to the inner surface thereof. This screen 36 is arranged to receive the material discharged over chute 34 and is provided with annular tracks 38 to engage rollers as 39, the said rollers 39 being mounted on shafts 40 and the shafts 40 being mounted in bearings 41 on base members 2. Shafts 40 are provided with bevel gears 42 engaging gears 43 on shaft 44, the latter being mounted in bearings 45 on base members 2 and driven by sprocket 46, chain 47 and sprocket 48 on 105 shaft 27. The material passing through cylinder 36 may be washed by a spray of liquid from a suitably arranged nozzle as 49.

When the device is in operation the nuts are dumped into hopper 5 directly from the 110 orchard. The nuts pass through openings 11—14 on to huller plate 23, the revolving of

said plate causing them to move outwardly between it and the brush 13 thereover, this operation removing the hulls from the nuts and discharging both the nuts and hulls beyond the periphery of plate 23.

Since the hulled nuts are thrown off of plate 23 with great force they may be seriously injured if hurled against a fixed and solid wall as shell 3. By arranging a buffer element as 18 to receive the impact of the nuts their lateral movement is arrested without injury to them and they fall, together with the hulls, upon plate 29. Since plate 29 is revolving in the direction indicated by the arrow both nuts and hulls are scraped off of plate 29 by member 35 into chute 34 through the orifices in which some of the hull portions pass. From chute 34 the remaining hulls and the nuts drop into cylinder 36 and are moved forward toward the discharge end thereof by spiral element 37. The mesh of cylinder 36 is such that all of the broken hulls drop therethrough so that by the time the hulled nuts are discharged from the cylinder they are cleaned and ready to spread out on trays for drying.

In order to more effectually clean the nuts and remove all substances that might stain them a spray of liquid is injected into the cylinder and over the nuts passing therethrough.

The operating mechanism is of course arranged to drive the plate 23, plate 29 and screen 36 at proper speeds to move the material thereover without congestion.

It is to be understood, of course, that while I have herein shown and described one particular embodiment of my invention, that this disclosure is to be considered as illustrative only and in no way to limit the scope of the invention as set forth in the appended claims, since changes in form, size, proportions, construction and method of operation may be made without departing from the spirit of the invention.

I claim:

1. A nut hulling machine including a revoluble huller plate, a brush mounted in spaced and substantially parallel relation thereto, means for feeding nuts to be hulled on to the central portion of said plate, and a buffer element mounted to receive the impact of the hulled nuts discharged by said plate.

2. A nut hulling machine including a revoluble huller plate, a brush mounted in spaced and substantially parallel relation thereto, means for feeding nuts to be hulled on to the central portion of said plate, a supporting ring mounted in spaced relation to said brush and concentric therewith, and a flexible buffer element depending from said ring.

3. A nut hulling machine including a revoluble huller plate, a brush mounted in

spaced and substantially parallel relation thereto, means for feeding nuts to be hulled on to the central portion of said plate, a receiver for the nuts and hulls discharged from said plate having a discharge opening therein, a revoluble bottom for said receiver, and a baffle plate rigidly mounted in said receiver to engage the nuts and hulls on said revolving bottom and direct them through said discharge opening.

4. A nut hulling machine including a revoluble huller plate, a brush mounted in spaced and substantially parallel relation thereto, means for feeding nuts to be hulled on to the central portion of said plate, a receiver for the nuts and hulls discharged from said plate, a revoluble bottom for said receiver, and means for directing said nuts and hulls from said bottom through said discharge opening.

5. A nut hulling machine including a revoluble huller plate, a brush mounted in spaced and substantially parallel relation thereto, means for feeding nuts to be hulled on to the central portion of said plate, a revoluble receiving plate for material discharged by said huller plate, means for simultaneously revolving both of said plates in the same direction and operating said huller plate at a higher speed than said receiving plate, and means for discharging material from said receiving plate when revolving.

6. A nut hulling machine including a revoluble huller plate, a brush mounted in spaced and substantially parallel relation thereto, means for feeding nuts to be hulled on to the central portion of said plate, a revoluble receiving plate for material discharged by said huller plate and having an upstanding flange thereon, means for simultaneously revolving both of said plates at unequal speeds, and a vertically positioned baffle plate rigidly arranged contiguous to said receiving plate and said upstanding flange, and having one portion thereof advanced in the direction opposite to the direction of movement of said plate.

7. A nut hulling machine including a revoluble huller plate, a brush mounted in spaced and substantially parallel relation thereto, means for feeding nuts to be hulled on to the central portion of said plate, a revoluble receiving plate for material discharged by said huller plate, means for simultaneously revolving both of said plates at unequal speeds, and means for discharging material from said receiving plate when revolving.

8. A nut hulling machine including cylindrical body member, a center-discharge hopper mounted thereover, a horizontally arranged brush depending from said hopper, a huller plate arranged to revolve in spaced relation to said brush and receive material

from said hopper, a receiver plate revolv-
bly mounted in said cylindrical body below
said huller plate and provided with an up-
standing flange of less diameter than said
5 huller plate and having a plurality of
equally spaced radially arranged orifices
formed therein within said flange, a driven
shaft, a gear connection between said shaft
and said huller plate, and a sprocket mount-
10 ed on said shaft in engagement with said
orifices in said receiving plate.

9. A nut hulling machine including a cy-
lindrical body member, a center-discharge
hopper mounted thereover, a horizontally ar-
15 ranged brush depending from said hopper,
a huller plate arranged to revolve in spaced
relation to said brush and receive material
from said hopper, rollers mounted on said
body member below said huller plate, a re-
20 ceiver plate mounted on said rollers and
provided with an upstanding flange of less
diameter than said huller plate and having a

plurality of equally spaced radially arranged
orifices formed therein within said flange,
a driven shaft, a gear connection between 25
said shaft and said huller plate, and a
sprocket mounted on said shaft in engage-
ment with said orifices in said receiving
plate.

10. A nut hulling machine including a 30
cylindrical body member, a center-discharge
hopper mounted thereover and having a
plurality of similarly arranged angularly
positioned slots formed therein, a horizon-
tally arranged brush depending from said 35
hopper, a huller plate arranged to revolve
in spaced relation to said brush and re-
ceive material from said hopper, and means
for adjusting said brush with relation to
said huller plate, said last mentioned means 40
comprising a bolt engaging each slot in said
hopper, a rigid support for each bolt, and a
locking nut mounted on each bolt.

JOSEPH A. CONNER.
